UNITED STATES PATENT OFFICE.

EDWIN R. EAVENSON, OF PHILADELPHIA, PENNSYLVANIA, ASSIGNOR TO
JAMES H. CATERSON AND ROBERT BROTZ, BOTH OF SAME PLACE.

DESIGN FOR THE BACK OF A PLAYING-CARD.

SPECIFICATION forming part of Design No. 14,810, dated February 26, 1884.

Application filed January 23, 1884. Term of patent 3½ years.

To all whom it may concern:

Be it known that I, EDWIN R. EAVENSON, a citizen of the United States, and a resident of Philadelphia, Pennsylvania, have invented 5 a new and Improved Design for the Backs of Playing-Cards, of which the following is a specification.

The nature of my invention is fully set forth in the accompanying illustration, to which reference is made.

What I claim as my invention is—

The design for the backs of playing-cards, as shown.

EDWIN R. EAVENSON.
